Primary Examiner — Alison M Oftun(74) Attorney, Agent, or Firm — Marshall, Gerstein & Borun LLP; Randall G. Rueth(57) CLAIM

The ornamental design for a cover for cosmetic products, as shown and described.

DESCRIPTION

FIG. 1 is a front perspective view of a first embodiment of a cover for cosmetic products, showing our new design; FIG. 2 is a front view thereof;

FIG. 3 is a rear view thereof;

FIG. 4 is a top plan view thereof;

FIG. 5 is a bottom plan view thereof;

FIG. 6 is a right side view thereof;

FIG. 7 is a left side view thereof;

FIG. 8 is a front perspective view of a second embodiment of a cover for cosmetic products, showing our new design; FIG. 9 is a front view thereof;

FIG. 10 is a rear view thereof;

FIG. 11 is a top plan view thereof;

FIG. 12 is a bottom plan view thereof;

FIG. 13 is a right side view thereof; and,

FIG. 14 is a left side view thereof.

The broken lines in the drawings illustrate portions of the cover for cosmetic products and form no part of the claimed design.
